DRINKING FOUNTAIN

Samuel L. Aub and William B. Long, Cleveland,
Ohio; said Long assignor to said Aub

Application February 6, 1939, Serial No. 254,864

3 Claims. (Cl. 299—16)

This invention relates to the general art of drinking fountains commonly found in factories and elsewhere.

Excessive perspiration takes from the system an appreciable quantity of salt which should be replaced. With this in mind, there is now being introduced in factories and other such places, the practice of providing salt tablets to be taken by the workmen with the water from the drinking fountain whenever desired. This, however, involves the preliminary act of taking the salt tablet, and this additional effort has proved discouraging, with the result that the purpose of the salt tablets has been largely defeated.

Therefore, the general object of the present invention is to provide a drinking fountain with means whereby salt may be supplied and taken at the same time and by means of the same single manipulation by the user, thereby avoiding the necessity of separate acts or operations, and whereby there may be obtained either salt water or plain water according to the desire of the user or medical advices, all with the same unitary device.

The more specific object of our invention is to provide separate valves for the water and salt solutions, respectively, there being provided a means of co-ordination between the two valves so as to permit either of the operations specified, this being accomplished by a single means manipulatable by the user.

Other objects will appear from the following description and claims when considered together with the accompanying drawing.

Fig. 1 is an elevation of the general assembly embodying our present form of invention;

Fig. 2 is a vertical section of the control mechanism;

Fig. 3 is a view taken on line 3—3 of Fig. 2; and

Fig. 4 is an end view of the operating lever or handle.

It is to be understood that the present form of disclosure is merely for purposes of illustration and that there may be devised various modifications without departing from the spirit of our invention as herein set forth and claimed.

The form of drinking fountain herein illustrated is intended to be typical and has the familiar bowl 1 mounted upon the wall, the bubbler 2 and the waste pipe 3 which discharges into the drain 4 and the outlet pipe 5.

Our improved valve control means is connected to the water supply pipe 6, the flow of water being controlled by the valve 7 which is adapted

to open and close the passage 8 leading to the tube 9. The passage 8 has communication through the annular groove 11 in the valve stem guide so as to be in constant registry with the passage 8 for all positions of the valve 10 and thus not interfere with the passage of water. The valve 10 is adapted to control the flow of salt solution from the container 12 through the pipe 13 and thence through the passages 14 and 15 and out through the upright tube 16 which is concentrically positioned within the water tube 9.

As will be noted, the valves 7 and 10 and their valve stems 7a and 10a are arranged for movement along substantially parallel paths. These valves are provided with coil springs 7b and 10b, respectively, which engage the valves at one end and suitable fixed abutments at the other ends, these springs tending normally to force the same towards closed position. The rotatable handle 17 has the valve stem 10a extending therethrough, with a nut 10c on the end of the valve stem for operative engagement by the handle 17 as it is turned. The inner side of the handle 17 has a multiple cam 17a, concentric with the valve stem, for co-operation with a companion multiple cam 18 in the thimble 19 which is non-rotatably mounted upon the end of the cylinder wall of valve 7. In this particular illustration, the thimble 19 has a cut-away portion for engagement with opposite sides of the neck portion 30 between the two valve casings. Thus the cam 18 is virtually fixed with respect to the valve casing, and any turning of the cam 17a with the handle 17 will cause an axial movement of the valve stem 10a towards the right, as viewed in Fig. 2, so as to open the water valve. This is true regardless of the direction of the turning movement of the handle 17, because of the multiple nature of the cam, as indicated in Fig. 3. We have provided the idle rollers 20 between the two companion multiple cams so as to ease the operation.

As clearly seen in Fig. 4, the handle 17 has a segmental ear 17a which is adapted to engage the nut 10c on the valve stem 10a when the handle 17 is turned in one direction. Such engagement of the nut 10c will cause the valve 10 to be opened since it will be moved towards the right, (Fig. 2), with valve 7. Thus, both valves 7 and 10 will be opened simultaneously or substantially so when the handle 17 is turned in one direction and there will be supplied a mixture of water and salt solution to the discharge nozzle of the drinking fountain.

When however, the handle 17 is turned in the

opposite direction, there will be no engagement of the nut 10c by the ear 17a, and the valve 7 alone will be opened while the valve 10 remains closed. In this case, only plain water will be supplied to the drinking fountain.

In the present illustration, the container 12 occupies position above the elevation of the discharge nozzle 2 and the small tube 16 is surrounded by the flow of water up through the tube 9 so as to have the salt solution drawn up thereby by the force of the water and discharged thereby with at the nozzle 2.

Thus, upon rotation of the handle 17 in one direction, (forwardly according to Fig. 2 of the present illustration), there will be effected a combined flow of water and salt solution; and upon rotation of the handle 17 in the opposite direction, there will be obtained a flow of plain water. With this device, it becomes a matter of extreme simplicity to obtain either plain water or salt water. In fact, the desired operation can be performed even with the eyes closed as there are no special or precise degrees of movement required in order to obtain the desired result, it being merely necessary to turn the handle in one direction or the other and without regard to the extent of movement, so far as obtaining the mixture or plain water is concerned.

The construction is so arranged that the handle 17 is located just below the basin 1 so as to be most conveniently operated by the hand of the user. This is made possible by the fact that there is no need for the user to observe the handle 17 during its manipulation, as above explained, especially after he once acquaints himself with the particular direction corresponding to plain water or salt water.

What we claim is:

1. In a device of the class described, a liquid supply line, a reservoir of solution to be mixed with the liquid, a pipe connection constituting the only means of communication from said reservoir to said liquid supply line, separate valves for separately and exclusively controlling the flow of the liquid and solution, respectively, to a discharge nozzle, means for setting the liquid valve in either of two open positions, operative means of connection actuated by the setting of said liquid valve in only one of its open positions for simultaneously opening said solution valve

also, whereby manipulation of said valve-setting means to one open position will open only the liquid valve and thereby effect a flow of plain liquid, and the manipulation of the valve-setting means to its other open position will open both valves and thereby effect a mixture of said liquid and said solution.

2. In a device of the class described, a liquid supply line, a reservoir of solution to be mixed with the liquid, a pipe connection constituting the only means of communication from said reservoir to said liquid supply line, separate valves for separately and exclusively controlling the flow of the liquid and solution, respectively, to a discharge nozzle, means operable in either of two opposite directions for setting the liquid valve in open position, operative means of connection actuated by the manipulation of said operable means in only one direction for simultaneously opening said solution valve also, whereby manipulation of said operable means in one direction will open only the liquid valve and thereby effect a flow of plain liquid, and the manipulation of said operable means in the opposite direction will open both valves and thereby effect a mixture of said liquid and said solution.

3. In a device of the class described, a liquid supply line, a reservoir of solution to be mixed with the liquid, a pipe connection constituting the only means of communication from said reservoir to said liquid supply line, separate valves for separately and exclusively controlling the flow of the liquid and solution, respectively, to a discharge nozzle, said valves being arranged in substantially parallel relation, said liquid valve having a handle rotatable in either direction for opening the same, and the solution valve being reciprocatable for opening and closing the same, cam means of operative connection rendered effective by the turning of said handle in only one direction for simultaneously opening said solution valve also, whereby rotation of the said handle in one direction will open only the liquid valve and thereby effect a flow of plain liquid, and the rotation of the handle in the opposite direction will open both valves and thereby effect a flow of a mixture of said liquid and said solution for discharge at the nozzle.
